UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

CIRCUIT-BREAKER.

1,300,367.

Specification of Letters Patent. Patented Apr. 15, 1919.

Application filed October 31, 1914. Serial No. 869,506.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Circuit-Breakers, of which the following is a specification.

My invention relates to circuit interrupters and it has particular reference to the utilization of condenser terminal bushings for decreasing the arcing and surging that is incident to the opening and closing of high tension electrical circuits.

The object of my invention is to utilize condenser terminal bushings for gradually changing the difference in potential between two conductors, that are either to be connected together or disconnected from each other.

It is well known that if the potential of two circuits, that are to be connected together, are of substantially the same value very little disturbance will be noticeable when actual connection is effected. It is further known, that, if the capacity between the contacts be increased at a greater rate than the break down voltage between the contacts increases, as the same approach each other, the disturbances incident to the engagement will be a minimum.

I provide a circuit interrupter that utilizes condenser terminal bushings for increasing the potential of one conductor when it is to be connected to another conductor of a higher potential in order that, at the instant before the two conductors are connected together, the difference in potential between the two will be low enough to prevent any serious surges or oscillations. By my invention the potential between two conductors may be gradually increased before the actual contact is broken, thus preventing the sparking or surging that is usually incident to opening a circuit.

The single figure of the accompanying drawing is a diagrammatic view of a circuit interrupter that embodies my invention.

A circuit interrupter 1 comprises an oil containing receptacle 2, two condenser terminal bushings 3 and 4, a movable bridging member 5 having two movable contact mem-

bers 6 and 7 mounted thereon; and a plurality of auxiliary stationary contact members 8 and 9, constituting pairs of contact members, that are so connected to the conducting layers of the condenser terminal bushings that the respective pairs of contact members are of substantially different potential one from the other. Two conducting rods 12 and 13 that are provided with main stationary contact members 10 and 11, respectively, on the lower ends thereof, extend through the condenser terminal bushings 3 and 4 and have line conductors 14 and 15 connected thereto at the upper ends thereof, respectively. It will be understood that the oil containing receptacle 2 and the outer layers 16 and 17 of the condenser terminal bushings are of a potential that is substantially the same as the ground potential, and, that the upper pair of the auxiliary conducting members 8 and 9 are so connected thereto that when the movable contact members 6 and 7 engage with the same, as shown in the drawing, there is no potential difference between the two.

In order to connect the conductor 14 to the conductor 15, which we will assume for the purpose of illustration to have a relatively high potential and a substantially ground potential, respectively, the movable bridging member 5 is moved downwardly to successively engage the corresponding pairs of auxiliary contact members 8 and 9. The difference in potential between the conductors 14 and 15 may thus be decreased until, at the instant before the main stationary contact members 10 and 11 are engaged, the difference in potential between the two conductors will be so small that no surge will traverse the conductors when the circuit is completed.

When it is desired to open the connection between the conductors 14 and 15 without sparking, the movable bridging member 5 is moved upwardly to increase the potential between the two by gradual steps, until the last auxiliary contact members are reached. In this position the difference in potential between the conductors 14 and 15 is a maximum.

It will be understood that should the capacity of the condenser terminal bushings not be sufficient, auxiliary electrostatic con-

densers may be placed in the tank 2 and electrically connected to the contact members 8 and 9.

While I have shown my invention in a simple and preferred form, it is not so limited, but is capable of various modifications within the scope of the appended claims.

I claim as my invention:

1. In a circuit interrupter, the combination with a condenser terminal bushing and a movable contact member, of a plurality of stationary contact members connected to points of different potential on the said condenser terminal bushing.
- 15 2. A circuit interrupter comprising a condenser terminal bushing, a movable contact member, and a plurality of stationary contact members operatively connected to the conducting layers of the terminal bushing having potentials that differ one from the other.
- 25 3. A circuit interrupter comprising two condenser terminal bushings, a movable bridging member having contact members mounted thereon, and a plurality of pairs of stationary contact members electrically connected to points of different potential on the said condenser terminal bushings.
- 30 4. A circuit interrupter comprising a main contact member, a condenser terminal bushing and a plurality of auxiliary contact members connected to the said condenser terminal bushings at points of potential that differ one from the other.
- 35 5. In a circuit interrupter, the combination with an oil-containing receptacle and

two condenser terminal bushings connected thereto and extending therein, of a movable bridging member having contact members mounted thereon, and a plurality of contact members electrically connected to the conducting layers of the said condenser terminal bushings.

6. A circuit interrupter comprising two condenser terminal bushings, a movable bridging member having contact members mounted thereon, and a plurality of stationary contact members electrically connected to the conducting layers of the said condenser terminal bushings.

7. In an electric circuit, the combination with a circuit interrupter having condenser terminal bushings, of movable contact members for coöperating with the terminal bushings to change the capacitance of the circuit in steps during the opening and closing operation of the interrupter.

8. The combination with two conductors, and a circuit interrupter connected therebetween having condenser terminal bushings, a means coöperating with the terminal bushings for so gradually changing the potential of the conductors that before they are connected together they have substantially the same potential.

In testimony whereof, I have hereunto subscribed my name this 28th day of Oct., 1914.

CHARLES LE G. FORTESCUE.
